UNITED STATES PATENT OFFICE.

ROBERT N. ROSS, OF ST. LOUIS, MISSOURI.

DISINTEGRATOR.

SPECIFICATION forming part of Letters Patent No. 443,838, dated December 30, 1890.

Application filed March 21, 1890. Serial No. 344,788. (No model.)

To all whom it may concern:

Be it known that I, ROBERT N. ROSS, of the city of St. Louis, in the State of Missouri, have invented a certain new and useful Improvement in Disintegrators, of which the following is a full, clear, and exact description, reference being had to the accompanying drawings, forming part of this specification.

My invention relates to an improved device for disintegrating or pulverizing ores, clay, and the like; and my invention consists in features of novelty, hereinafter fully described, and pointed out in the claim.

Figure I is a top or plan view illustrative of my invention. Fig. II is a vertical section through the cages of the machine, this section being taken on line II II, Fig. III. Fig. III is a horizontal section, taken on line III III, Fig. II. Fig. IV represents two detail views illustrating the manner of connecting the rounds to the rings of a cage.

Referring to the drawings, 1 represents a suitable frame-work, provided with boxes 2, in which is journaled a continuous shaft 3, provided with driving or operating pulleys 4.

5 represents a cylinder through which the shaft 3 passes and which comprises a number of movable cages and a number of fixed cages, each cage being composed of rings through 30 which connecting-rounds pass. One head 6 of the cylinder is provided with a hub 7, through which the shaft 3 passes and which is rigidly secured to the shaft, so as to be turned thereby. The other head 8 of the cylinder is rigidly connected to the frame of the machine, preferably by means of bolts 9. (See Fig. III.)

10 represents an outer annular series of rounds secured to and carried by the head 6; 40 11, an annular intermediate series of rounds secured to and carried by the head 6; and 12, an inner annular series of rounds secured to and carried by the head 6.

13 represents an annular series of rounds 45 secured to and held by the head 8 and located between the movable series 10 and 11, and 14 represents an annular series of rounds secured to and held by the head 8 and located between the series 11 and 12 of the movable

50 rounds.

15 represents three rings fitted respectively

on the outer ends of the rounds 10, 11, and 12, and which are carried thereby.

18 represents three rings fitted respectively on the series 10, 11, and 12 of the rounds near 55 the centers of the latter; and 19 represents three series of annular rings fitted respectively on the inner ends of the rounds 10, 11, and 12, close up against the head 6.

20 represents two rings fitted respectively on the outer ends of the rounds 13 and 14.

21 represents two rings fitted respectively on the rounds 13 and 14 near their centers, and 22 represents two annular rings fitted respectively on the inner ends of the rounds 13 65

and 14 at their inner ends close up against the head 8. The function and office of these rings 15, 18, 19, 20, 21, and 22 are to steady and support the rounds, making them rigid and firm, so as not to give or move in their 70

supports when the machine is in use, the central rounds serving also to separate the material. The center of the cylinder formed of these cages composed of the rings and rounds is left open, as shown at 23, and the stuff or 75

material to be disintegrated is fed or discharged into the open center of the cylinder, and works its way outwardly through the different cages to the periphery of the cylinder, where it is discharged. By making the inner 80 cage a revolving one, the stuff is forced to feed outwardly from the center of the cylinder, and by making the outer cage movable the cylinder is self-delivering.

I have shown and described an intermediate movable cage; but this might be dispensed with, it only being essential to have one or more stationary cages and two or more movable cages, the inner and outer cages being movable, so that the stuff will be fed into 90 and discharged from the cylinder. By an arrangement of this kind the supporting and operating shaft 3 can be extended through the cylinder and have a firm support on each side of the cylinder, thus preventing the lag- 95 ging or displacement of the movable cages relatively to the fixed cages, and consequently avoiding any friction which would result from the movable cages being thrown out of line with the fixed cages, and which would result 100 from a bearing of the shaft on one side only of the cylinder.

I am aware that disintegrators consisting of stationary and movable cages of similar construction to those herein described are well known; but this is not the same as my 5 invention, which consists in the specific arrangement which renders the machine self-feeding and self-delivering.

I claim as my invention—

10 In a disintegrator, the combination of a suitable frame, a shaft, and a cylinder through

which the shaft passes, said cylinder being composed of fixed and movable cages, and said cages consisting of series of rounds with end and central securing-rings, which also serve to prevent lateral shifting of the material, substantially as set forth. 15

ROBERT N. ROSS.

In presence of—

E. S. KNIGHT,

THOMAS KNIGHT.
